US0D1084013S

(12) **United States Design Patent** (10) Patent No.: **US D1,084,013 S**
 Lofberg et al. (45) Date of Patent: ** Jul. 15, 2025

- (54) **DISPLAY SCREEN OR PORTION THEREOF WITH A GRAPHICAL USER INTERFACE**
- (71) Applicant: **Canva Pty Ltd**, Surry Hills (AU)
- (72) Inventors: **Martyn Lofberg**, Eagle Vale (AU); **Melanie Joy Perkins**, Sydney (AU); **Matthew Hardy**, Surry Hills (AU); **Hannah Heffernan**, Darlinghurst (AU); **Cameron Adams**, Rozelle (AU)
- (73) Assignee: **CANVA PTY LTD**, Surry Hills (AU)
- (**) Term: **15 Years**
- (21) Appl. No.: **29/853,328**
- (22) Filed: **Sep. 14, 2022**
- Related U.S. Application Data**
- (60) Continuation of application No. 29/700,858, filed on Aug. 6, 2019, now Pat. No. Des. 967,843, which is a division of application No. 29/623,953, filed on Oct. 27, 2017, now Pat. No. Des. 861,023.
